F. A. FRASER

LIFTING JACK

Filed Dec. 8, 1922

Inventor

Fleming A. Fraser
By his Attorney, J. L. Levy

UNITED STATES PATENT OFFICE.

FLEMING A. FRASER, OF NEW YORK, N. Y.

LIFTING JACK.

Application filed December 8, 1922. Serial No. 605,575.

To all whom it may concern:

Be it known that I, FLEMING A. FRASER, a citizen of the United States, and resident of the city, county, and State of New York, have invented a certain new and useful Improvement in Lifting Jacks, of which the following is a specification.

This invention relates to an improvement in a lifting jack, particularly one of such form that it is specially adaptable for automobile use or the like.

The object of this invention is to provide a device consisting of but few parts so constructed that the device will be practically unbreakable; to provide a device in which the customary pawl and ratchet mechanism is not used, and to produce a device which will be extremely effective in operation and simple in construction.

With these objects and other objects which may hereinafter appear, in view, I have devised the particular arrangement of parts hereinafter set forth and more particularly pointed out in the claims appended hereto.

Reference is to be had to the accompanying drawing forming a part hereof in which

Figure 1 is a side elevation of a lifting jack made in accordance with my invention, parts being shown in section to disclose construction.

Figure 2 is a sectional view on the line 2—2 of Figure 1 looking in the direction of the arrows.

Figure 3 is a sectional view on the line 3—3 of Figure 1 looking in the direction of the arrows, and

Figure 4 is a side elevation of my improved lifting jack showing the same in its lowered position.

Throughout the various views of the drawings, similar reference characters designate similar parts.

In the preferred embodiment of my invention, as disclosed in the accompanying

drawing, 1 indicates a base of the jack which consists of a flat section of material provided with a pair of spaced uprights 2 between which the lever 3 is pivoted.

A pin 4 extends through the uprights 2 and the lever 3 and acts as a bearing pin for the lever. The lever 3 may be of any desired length and if desired, may be foldable or telescopic to permit the device to be carried compactly in an automobile.

This lever 3 is provided with a handle end

and the opposite end 5 of said lever constitutes the lifting or load-bearing end.

The end 5 of the lever is connected to a pair of downwardly depending links 8 by means of a pin 7 which extends through the lever 3 and into slots 9 in the links.

These links 8 are located on opposite sides or faces of the lever 3 and are pivotally connected at their lower ends to a block 10 by means of the pin 11 which passes through the lower ends of the links 8 and through the upper end of the block 10.

The lower end of the block 10 is provided with a weight 12 which tends to cause the block 10 to at all times assume a vertical position.

The block 10 is provided with an eye 13 and from this eye 13 to another eye 15 secured to the lever 3 extends a cord or cable 14 for a purpose to be hereinafter described.

From the foregoing, the operation of my improved lifting jack will be readily understood.

In Figure 4, the device is shown in its lowered position, and in the position it assumes when thrust under a car axle or the like to lift the same. When in this position, it will be seen that the block 10 rests at an angle upon the base 1 and the pin 7 in the lever 3 is at the upper end of the slots 9 in the links 8.

When downward pressure is exerted upon the handle 6 of the lever 3, the car is raised and the block 10 swings forward to a vertical position which it assumes readily by reason of its weighted lower end 12.

The load-bearing end 5 of the lever 3 may then be lowered slightly until it rests down upon the upper end of the block 10, which it can readily do, due to the fact that it is movable independent of the links 8 by reason of the pin and slot engagement therewith.

The device, in its position of supporting a load, is shown in Figure 1 where it will be seen that the pin 7 is at the lower end of the slots 9 and the load-bearing end 5 of the lever 3 is resting firmly upon the upper end of the block 10.

To lower the jack, a cable or cord 14 is pulled so that the block 10 is swung about its axis 11 to the position shown in Figure 4 which causes the load-bearing end 5 of the jack to be lowered.

At 16 and 17 are shown stops which act to regulate the pivotal movement of the links 8 to hold them in a more or less vertical position and to restrict undesirable swinging 5 movement of said links.

One of the features of my construction is that through the connection of the block 10 to the lever 3 by means of freely movable links, the block 10 is held vertical at all 10 times to support the load.

From the foregoing, it is obvious that my invention is not to be restricted to the exact embodiment shown but is broad enough to cover all structures coming within the scope 15 of the annexed claims.

What I claim is:—

1. A device of the class described comprising a pivoted lever and means for supporting the same, said lever having a load-bearing end and a handle end, a link connected to said load-bearing end and a supporting block pivotally connected to said link.

2. A device of the class described comprising a pivoted lever and means for supporting the same, said lever having a handle end and a load-bearing end, a pair of links pivotally secured to the load-bearing end in such manner as to permit said lever to have 30 movement independent of said links and a

supporting block pivotally connected to the lower ends of said links.

3. A device of the class described, comprising a pivoted lever, a support therefor, a pair of links pivotally secured to one end 35 of said lever, each of said links being provided with a slot, means on the lever freely movable in said slots and a block pivotally connected to the lower ends of said links.

4. A device of the class described comprising a pivoted lever, means for supporting the same, said lever having a load-bearing end and a handle end, a link located on each side of said lever at the load-bearing end thereof, a pin on said lever extending 40 through the slots in said links, a block pivotally connected to the lower ends of said links, said block having a weighted lower end, and a connection between said block and said lever.

5. A device of the class described comprising a pivoted lever, a pair of links connected to said lever at one end thereof in such a manner as to permit slight movement 55 of said lever, independent of said links, and a block pivotally secured to said links and provided with a weighted lower end.

Signed at the city, county and State of New York, this 29 day of November, 1922.

FLEMING A. FRASER.
